[57]

ABSTRACT

A washing machine with a front-loading washing and drying chamber, including a slideable rack for the suspension of garments to be washed by a set of spray nozzles, is provided with a narrow air shaft rising alongside the treatment chamber and communicating with it at the top and bottom, the air being circulated in a drying phase along a closed path by a blower above the chamber. A sprinkler disposed in the upper part of the air shaft serves to condense the steam entrained with the circulating air, its jets being intercepted by a textile liner on the shaft wall which guides the water down to a collecting trough at the chamber bottom. In a washing phase, with the spray nozzles operating, solution accumulating in the trough is recirculated after reheating by a heater split into two sections, one of them being energized continuously during a warmup period while the other is energized only during standstill of the intermittently operated recirculation pump.

WASHING MACHINE

The invention relates to an automatic machine which is controlled by a program selector for washing articles, in particular non-ironing garments, by washing, rinsing and drying them whilst they are hanging up in a washing and drying chamber located inside the machine, which is provided at the top with tooth-like rods on which the garments can be hung as well as with sprinklers for the washing solution or water which is to be pumped around, and is supplied with circulating drying air in order to provide heat and dry up the moisture. The washing, rinsing, finishing and drying of the garments in the hanging position which is characteristic of such machines ensures a mechanically gentle washing and general good care of the garments, which is of great practical importance particularly when washing non-ironing laundry items which are sensitive to mechanical stress.

In a machine of the above type, support rods arrayed like the teeth of a comb are fixedly arranged in the upper part of the washing and drying chamber of the machine so that, in order to introduce and remove the washing, the lid of the machine must be lifted up. Furthermore, the spray tubes for the supply of soap solution and rinsing water are arranged only in the upper part of the washing and drying chamber so that the laundry items which are hung up and are to be washed can be sprayed with suds solution and rinsing water only from the top or from the outside. Moreover, the continuous supply of suds solution leads to undesired reductions in the flow pressure of the solution since the foam which forms reduces the efficiency of the feed pump which circulates the liquid in an uncontrollable way. It has also been shown that the desired drying effect cannot be fully obtained by circulating drying air which flows up through the washing and drying chamber from the bottom because it results in undesired chimney effects whereby the warm drying air can pass through the empty spaces between the individual items without coming into sufficient contact with the garments.

The invention is concerned with improving and perfecting a washing machine of the general type mentioned above so that it is free of the aforesaid disadvantages, and is more economical to operate and easier to load while enabling more effective washing, rinsing, finishing and drying of the garments hanging in it.

This object is achieved in accordance with the present invention by mounting the support rods on a carriage which can be drawn out at the front of the machine, at least one additional spray tube being located in the lower part of the washing and drying chamber; the suds solution is recirculated intermittently, and the circulating drying air is made to pass from top to bottom through the washing and drying chamber. Loading of the washing machine is substantially facilitated by the garment rods which are preferably hinged onto the movable carriage and able to be locked in an upwardly swung horizontal position, since the individual laundry items can be quite easily hung on and later removed from the rods of the carriage when the latter is pulled out at the front of the machine. Furthermore since the spray tubes are arranged not only at the top but also at the bottom of the washing and drying chamber, preferably in the form of a spray arm rotating about its vertical central axis, the garments hanging on the rods can now be effectively flushed with suds solution and rinsing water both from the bottom and in between, whereby the washing and finishing effect is substantially improved. Also, despite the formation of foam through the intermittent pumping of the suds solution, a higher flow pressure of the suds can nevertheless be maintained at least periodically in the spray tubes. Furthermore a better drying effect is achieved by the passage of the circulating drying air through the washing and drying chamber from top to bottom in that the drying air is so to speak automatically distributed within the washing and drying chamber according to its temperature. The relatively hot dry air flowing in at the top of the drying chamber tends to stay in the upper part of the chamber until it is cooled through absorption of the moisture in the garments and then sinks to the bottom. Thus

turbulent chimney effects are avoided and the contact time with the drying air necessary for drying the garments is correspondingly reduced.

According to a further feature of the invention there is provided, in addition to the washing and drying chamber and separated therefrom by a vertical partition, a narrow shaft for the circulated drying air which is supplied with cooling means and connected at the top and bottom with the washing and drying chamber. A sprinkler may serve as the cooling means, preferably in the upper part of the air shaft, at about a third of the height from the top, so that the jets of the sprinkler are directed onto the outer wall of the air shaft. The latter is has a wall lined with an absorbent mesh of textile material for the downwardly flowing cooling water whereby water particles are prevented from being carried along by the circulating air flowing past. The circulating blower and the heating device for the circulating drying air which flows into the upper part of the washing and drying chamber are preferably arranged at the upper end of the air shaft. Thus there results as a whole an extremely compact assembly for guiding, cooling and reheating the circulated drying air and at the same time a very advantageous arrangement of the tank collecting the suds solution and water.

The circulating pump is arranged in accordance with the invention to be driven intermittently, each rest period of the circulating pump being longer than its pumping time, preferably at least three to four times as long, and lasting for at least about 10 seconds. We have found that, to wash and rinse a normal load effectively, the circulating pump (which is preferably driven by a pole-changing motor) should produce at the entrance to the individual spray pipes a minimum flow pressure of 0.5 atmosphere whereas for washing and rinsing sensitive fabrics, such as wool, as well as in certain rinsing stages of a normal wash, this minimum fluid pressure can be reduced to about two-thirds or one-half of the normal pressure.

The costs of such circulating pumps increase with the rate of flow i.e. the fluid quantity supplied thereby per unit of time with constant delivery pressure. The rate of flow can, however, be reduced without impairing the results of the wash if, according to a further feature of the invention, a changeover valve is arranged between the pressure connection of the circulating pump and the upper and lower spray pipes. Depending upon its position, this filter admits fluid to different groups of spray pipes. During the rest periods of the pump the changeover valve can be switched over to the next group of spray pipes.

Furthermore, the invention also provides for an improved utilization of the electrical generated thermal energy with regard to the intermittent drive of the circulating pump. This improvement is achieved in that heating of the suds solution is effected by two separately operable heating elements one of which is permanently switched on during the heating-up phase whereas the other, whose electric-power consumption preferably corresponds to that of that pump, is switched on only during the rest periods of the circulating pump.

In order to attain an overall uniform and intensive cleaning action within the garment, particularly in the upper region, in the case of larger laundry items, the garments hanging on the rods are moved to and fro in an essentially horizontal direction at least during certain phases of the washing, rinsing and drying process. The individual layers of the garments which hang in folds are thus opened up and rubbed together whereby the insides of the garments are at once more easily accessible to the suds solution, rinsing water, and drying air and are additionally subjected to further mechanical cleaning action, both of which factors lead to an improvement in the degree of uniformity of the wash and simultaneously reduce the processing time.

By way of illustration, machines embodying the invention are described below with reference to the accompanying drawing, in which:

FIG. 1 is a perspective view of a washing and drying chamber of a machine according to our invention, partly in section, with adjoining chambers for the circulation of drying air;

FIG. 2 is an end view of the machine of FIG. 1 but with a modified lower spray-pipe formation;

FIGS. 3 and 4 are detailed views of a spray pipe and of a spray arm rotatable about its vertical central axis, respectively;

FIGS. 5 and 6 show a garment holder in detail, idle and in use, respectively;

FIG. 7 is a sectional side view of a hinged mounting of a garment-support rod on the garment carriage;

FIG. 8 is a rear view of the rear side wall of the washing and drying chamber with spray pipes which are pivotally mounted thereon for pendulum-like oscillatory movement;

FIG. 9 is a schematic view of the circulation system for the suds solution and water;

FIG. 10 is a diagrammatic view of a modified washing machine;

FIG. 11 is a vertical sectional view taken through another washing machine, parallel to its front;

FIG. 12 is a cross-sectional view of the machine displaced by 90° from that of FIG. 11;

FIG. 13 is a diagrammatic sectional view of modified garment-support rods provided with hinged suspended bars;

FIGS. 14 and 15 are vertical sectional views through a further preferred embodiment of the invention, seen respectively parallel to the loading door and transversely;

FIGS. 16 and 17 are vertical sectional views of two different types of machine doors;

FIG. 18 is a circuit diagram of the control system for the heating of the drying air;

FIG. 19 shows a circuit for the control of the drive of a rotary pump;

FIG. 20 is a time chart for a pair of cam plates of a program selector included in the circuit of FIG. 19;

FIG. 21 shows a circuit for heating the suds solution and driving the circulating pump; and

FIG. 22 is a time chart of a pair of cam plates of a program selector included in the circuit of FIG. 21.

As can be seen from FIGS. 1 and 2, parallel rods 2 are provided in the upper part of the washing and drying chamber 1 of the machine and are hinged to a garment carriage 4, at a transverse bar 4' thereof, which can be extended out through the door 3 at the front of the machine. For this purpose, as is apparent from FIG. 7, lugs 4" projecting from the transverse bar 4' of the carriage 4 have each a longitudinal slit 4''' as well as a cradle 4" for respective crossbolts 2', 2" which are located on the rods 2, these rods being generally U-shaped in cross-section and open downwardly. Whereas the bolt 2' passes through the longitudinal slit 4''', the bolt 2" rests in the recess 4" of the associated lug 4" bracketed by the U-profile. The garment rods 2 are thereby locked or firmly maintained in their upper position, as shown in FIG. 7, whereas for folding down they need only be raised and drawn forward so that the crossbolts 2" can swing down past the front edges of the lugs 4". For loading and unloading the washing and drying chamber, the rods 2 are drawn out together with the carriage 4 through the door opening 3 located at the front of the machine whereupon the individual laundry items can be easily hung on or removed from the rods 2. In order to prevent, for example, a shirt which is hanging on a rod, or a sheet which has been folded once down the middle, from catching on the lower edge 3' of the door opening during each inward and outward movement of the carriage 4, the clear height H of the door opening should amount to at least about 1 meter and the cupboard-like machine should thus be of a suitable overall height.

Upper spray pipes 5 with flat discharge nozzles 6 are arranged at a distance WA (see FIG. 2) above the garment rods 2. The number of spray pipes 5 is limited to a maximum of five altogether for reasons of design economies of the circulating pump, so that about three spray pipes 5 are arranged in the

upper part of the washing and drying chamber 1 while either a pair of pipes 5, as shown in FIG. 1, or a single spray-pipe arm 7 rotating about its vertical central axis, as shown in FIG. 2, is provided in the lower part of the chamber. This type of rotating spray-pipe arm 7 can be advantageously used also in place of the upper spray pipes 5. Whereas the supply of water or suds to the individual nozzle carriers or spray arms 5 takes place from one side at their rear ends, the rotating spray arm 7 is fed from below in the middle, as shown in FIG. 4. Spraying of the laundry items from the top and bottom has proved advantageous particularly with cumbersome articles which during the washing and rinsing steps hang folded over the rods 2, because then the insides of the items which hang down in U-shaped folds can be sprayed directly. The shape of the spray pipes 5 and the spray nozzles which project out therefrom is of special importance to the washing and smoothing of the garments. For this purpose, the spray pipes 5 are provided with flat discharge nozzles 6 of the kind which can be seen in particular from FIG. 3. The ends of the spray nozzles 6 are flattened or compressed. In this way, straight concentrated jets 8 of suds or water emerge which meet the individual laundry items broadside and with a comparatively large amount of kinetic energy, owing to the arrangement of the spray pipes 5 parallel to the rods 2. Through this blast action, on the one hand, and the thermoplastic action in the hanging garments which occurs at the processing temperatures, on the other hand, the garments are stretched and effectively smoothed. In order to let the flat jets pass all over the entire cross-sectional area of the washing and drying chamber 1 and thus also over all the items which have been hung up, the spray pipes 5 can be pivotally mounted about their longitudinal axes on the rear wall 1' of the washing and drying chamber and may be displaced during the washing and rinsing steps by an electric motor so as to oscillate in the manner of a pendulum. One suitable mechanism for this purpose is illustrated in FIG. 8 in which the spray pipes 5, whose rear ends 5' project rearwardly out of the machine wall 1', are shown hinged to a common connecting rod 9 by guide rods 5", the rod 9 being connected by means of a pitman 9' with a crank disc 9" which is rotatably driven by an electric motor. The resulting oscillations of the spray pipes 5 have been symbolized by the double-headed arrows in FIGS. 1 and 2. The distance WA between the upper spray pipes 5 and the rods 2 which are located below them should amount to at least one-third of the spacing between adjacent spray pipes, so that the downwardly directed jets of suds and water can better penetrate into the spaces between the garments.

Alongside to the washing and drying chamber 1 and separated therefrom by a vertical partition 10 there is provided a narrow air shaft 11 for the circulated drying air, this shaft being supplied with cooling means and connected at the top and bottom with the washing and drying chamber by way of ducts 12, 13 which extend essentially horizontally. The air shaft 11 is provided in its upper part, at about the upper third of its height, with a spraying device 14 from which jets of cooling water are directed on to its outer wall 15. In this way, the circulating air, which moves in the direction of the arrows, is effectively cooled when passing upwardly through the air shaft 11 so that the moisture contained in the air stream is condensed, the air being correspondingly dried. In order to circulate the drying air, a blower 16 (FIG. 10) is provided in the upper connecting duct 13, between the air shaft 11 and the washing and drying chamber 1, and a heating device 17 for the circulating air is coupled to the outlet side of the blower. By this heating device 17, the drying air, which has previously lost its moisture in the shaft 11, is reheated so that on subsequently passing through the washing and drying chamber from top to bottom it can again absorb moisture from the garments.

The lower connecting duct 12 is separated from the washing and drying chamber 1 above by a perforated base plate 18 and serves at the same time as a suds-and-water-collecting tank. In the embodiment of FIG. 2 the base plate 18 is mounted on the rotating spray arm 7 so that it takes part in the rotary motion

of the arm during washing and rinsing. The base plate 18 is here formed as a circular disc covered at its edge by an annular flange 18' which leaves free the major part of the disc and is attached to the wall of the housing. It will be evident that the base plate 18 could also be fixed beneath the rotating spray arm 7. The lower part of the collector 12 defines a storage tank 12' in which is located an electric heater 19 for the suds solution or rinsing water discharged by way of a drain 12.

As shown in FIG. 9, the suds solution and rinsing water are guided from the tank 12' through a conduit 20 to a circulating pump 21 and then via a high pressure branch 22 to a water switch 23 from which the circulating liquid passes out through conduits 24, 25 to the spray pipes 5. The circulating pump 21 can be driven by a pole-changing motor 26 and the water switch 23 by an electric motor 27, which are both controlled in known manner by a program selector 28 and associated relays.

Both the perforated base plate 18 of the washing and drying chamber 1 and a grating 29, which covers the tank discharge pipe 12" and whose mesh size is smaller than the width of the spray nozzles 6 in order to avoid any blockage by threads or other impurities, are arranged to be removable so that they can easily be cleaned.

Several spacing bars 30, one of which is shown in FIGS. 5 and 6, can be deposited on the rods 2 and consist each of an oblong, generally U-shaped hollow member which is provided over its entire length with slits 31 for the passage of water and air. These spacing bars 30 are, as shown in FIG. 6, used to permit several garments 32, 33 to be hung one over another on the same support rod 2 with suitable spacing whereby because of their shape and design they improve the penetration and diffusion of the suds, rinsing water and drying air and thus generally ensure a more effective cleaning and drying of the individual garments hanging one over the other.

FIG. 10 illustrates the entire machine in a diagrammatic and partly sectional view. The side walls of the washing and drying chamber 1 are provided with a heat-insulating layer 34 which is surrounded by an outer lining 35. The front opening 3 is closed by a door panel 36 which, by means of a rubber gasket 37, provides a watertight closure of the machine. The perforated plate 18 which forms the lower cover, the two spray pipes 5 as well as the support rods 2 of the extensible carriage 4 in the inserted position are all visible through the open door. The upper closure of the machine is formed by a control panel 38 with adjustment knobs, indicators and keys for the program selector as well as by a soap basin 39 which can be swung out about a lateral vertical axis. The hollow pivotal axle 40 of the basin 39 at the same time forms a tubular connection to the washing and drying chamber 1 through which detergent can be passed into this chamber at appropriate times. The lower part of the outer lining 34 is shown broken away to give a view into the air shaft 11 which in the upper third of its length contains the spray device 14 for condensing the steam. The washing and drying chamber rests on two foundation plates 41 and is connected therewith by stays 42.

The washing machine illustrated in FIGS. 11 and 12 is likewise in the shape of a cupboard of approximately a man's height. The washing and drying chamber 101 is separated from the cupboard-like outer housing 102 by heat-insulating and sound-absorbing layers 103 and is closed at the front by a door 104. The door 104 is double-walled and defines a space 105 between its walls 104', 104" which opens into the washing and drying chamber 101 at the top through a labyrinth-like passage 106 and at its lower end 105' communicates freely with the outside. The space 105 serves for pressure equalization and at the same time as an overflow and foam outlet for the washing and drying chamber 101. Above the door 104 is located the electric control panel for the program selector (not shown) which is set behind the panel and above the washing and drying chamber, the panel being provided with a row of keys and corresponding control buttons.

The washing and drying chamber 101 has an inclined base 108 which slopes to one side of the machine; a circulating

pump 109 for the suds solution and rinsing water and a driving motor 110 for the pump are arranged beneath the higher part of the base. The pump 109 is connected through an intake duct 111 with the lower part 101' of the washing and drying chamber 101, which is filled with suds or rinsing water during the washing, rinsing and smoothing stages; a liquid-heating element 112 is also located in the washing and drying chamber. Furthermore, beneath the base 108 there is an exhaust pump 113 which is attached to an outlet port 115 by an intake pipe 114 and leads outwardly to a drain (not shown) through its discharge pipe 116. A cold-water pipe (not shown) leading to the machine opens into the upper part of the washing and drying chamber.

On one longitudinal side of the machine is located an air and condensation shaft 118 which is separated from the washing and drying chamber 101 by a partition 117 and which is supplied during the drying process with sprays of cold water by way of a pipe 119, the function of the water being to cool down the drying air which flows upward through the shaft 118 and thus to remove moisture therefrom. In order to ensure a thin uniform distribution of the cooling water, which trickles downwards, and to prevent the air which flows upwards from taking the water along with it, the sprayed outer wall of the condensation shaft 118 is covered with a fine-mesh textile fabric forming a water-absorbing liner 120. Moreover, on the lower edge of the partition 117 facing the washing and drying chamber 101 there is located a condensed-water trap 121 which keeps the condensate away from an air-inlet slit 122 located therebeneath and leading to the air and condensation shaft 118, thereby preventing the condensed water, which could otherwise drip off the partition 117 into the slit 122, from being carried along by the air stream. The upper part of the 118 which is situated above an inclined lid 123, extending substantially parallel to the inclined base 108, contains a heater 124 adjacent a driving motor 125' of a ventilator 125 for the circulating drying air, designed as a cross flow fan. The air can be blown into the washing and drying chamber 101 in a sufficiently dry and heated state by way of an outlet slit 126 located in the inclined lid 123. An air distributor 127 is provided beneath the outlet slit 126 and consists of several diverging air deflectors 127' arranged in an arcuate array. Moreover, a basin 128 for the detergent and rinsing agent is provided on the lid of the housing.

The upper part of the washing and drying chamber 101 is provided with a garment carriage or bearer 129 which can be moved out at the front of the machine and is provided with hinged rods 130, arranged like the teeth of a comb, for laundry items 131 which are to be hung up thereon. Beneath these rods 130 there are provided two similarly comb-like slide rails 132, 133 which serve as a garment mover and can be moved to and fro in opposite horizontal directions, the prongs 132', 133' of the rails running parallel to the superposed rods 130 and having a smaller cross-sectional area than the latter so as not to hinder inward movement of the garments on the carriage 129. The to-and-fro movement of the garment mover indicated by the arrows is caused by an appropriate design and operation of the slide rails 132 and 133. The latter can be moved to and fro at least during specific stages of the washing, rinsing and drying cycle so that the articles hanging on the rods 130, particularly bulky and folded articles, undergo an adequate aerating and cleaning motion during these working stages and are in particular effectively supplied on the inside with suds, rinsing water and drying air.

Another form of garment mover is illustrated in FIG. 13. Here the garment mover consists of mobile bars 134 of flattened U-shape which are articulated at their ends to the movable garment rods 130 by hinge joints 135. Each bar 134 has an arm 136 located eccentrically of the axis which runs through the hinge joints 135, the bars being made to oscillate by a reciprocable driving rod 137 having elbows 138 engaging the arms 136. The oscillations as well as the to-and-fro motions of the driving rod 137 are indicated by the double arrow. The oscillatory drive of the rod 137 can derive from an electric or

hydraulic motor. As can be seen in FIG. 13, the ability of the rods 130 to fold down is not impaired by the mobile bars 134 and their driving connection with the rod 137.

In the embodiment of FIGS. 11 and 12, the supply of suds and rinsing water is effected by way of a U-shaped spray rack 140 arranged in the washing and drying chamber 101, the arms of this rack forming respectively upper and lower spray pipes 141, 142 interlinked by a tubular crosspiece 144 which runs adjacent the rear wall 143 of the washing and drying chamber and is pivotally mounted so as to be swingable about a horizontal axis 145 which runs approximately through the center of the washing and drying chamber 101 and through the center of the crosspiece. The drive can be taken from an electric or hydraulic motor. The spray rack 140 is connected through its pivotal bearing hub 146 to a high line 147 leading from the circulating pump 109. The two pipe halves 144', 144'' of crosspiece 144 afford independent supplies of suds and rinsing water to the arms 141, 142 and as shown in FIG. 12, open separately into the pivotal bearing hub 146 where they are supplied both individually and jointly with suds and rinsing water through a changeover valve which is connected in circuit and preferably incorporated directly in the pivotal bearing 148. It has proved particularly advantageous to design and regulate the changeover valve installed in the supply line so that during the washing step mainly the lower arm 142 is supplied with suds and rinsing water, during the smoothing step both arms 141, 142 are supplied alternately, and during the rinsing step both arms are supplied jointly. Flat discharge nozzles 141', 142' located in the arms 141, 142 of the spray rack run parallel to the garment-support rods 130 and thus produce cones 141'', 142'' of spray which with the swinging motion of the rack 140, indicated by the large double arrow in FIG. 11, meet the broad surface of the hanging articles in continually alternating directions, thereby intensively beating the articles and imposing on them additional to-and-fro motion. In order to obtain a sufficient outlet pressure at the spray nozzles with a conventional and economic circulating pump 109, the latter is driven intermittently, specifically so that the standstill periods of the circulating pump during the washing process amount to at least three or four times its operating time, that is to at least about 10 to 15 seconds. During the standstill periods, the suds flowing to the circulating pump 109, largely in the form of foam, have the opportunity to achieve sufficient concentration so that they can be supplied to the pipe arms 141, 142 by the circulating pump with full, even if only temporary, pressure.

In the modified washing machine illustrated in FIGS. 14 and 15, a washing and drying chamber 211 is separated from an air shaft 221 by a vertical partition 203. The laundry items are hung up on comb-like rods 202 for the duration of the washing, rinsing, smoothing and drying process. Above the rods 202 are located two spray pipes 205 which are pivotable about their longitudinal axes and are connected in the same way as a lower rotating spray arm 204 to the circulating system for the suds and rinsing water (not shown) which is operated by a circulating pump 201. The pump inlet is connected with a collecting tank or base trough 206 above which is located a heater 207.

In order to dry the washed and rinsed garments hanging on the rods 202, the air in the machine is circulated by a powerful cross-current blower 208 as a heat and moisture carrier. This blower is tightly connected, by an annular sealing flange 209 on housing 212, through an interposed packing with the housing of the machine, i.e., with the wall of the washing and drying chamber 211. In order to prevent steam or foam (during the washing process) and moist air (during the drying process) from leaving the generally open front sides of the blower housing 212, the housing is closed in an airtight manner, the drive shaft 213 being sealed by conventional means. The transverse-current blower 208 supplies air, issuing from the shaft 221, which air has been sufficiently dried through condensation at a fabric liner 224 and properly heated by passing by a heater 232, through one or more inlet orifices 214, into the washing and drying chamber 211.

The transverse-current blower is, as shown in FIG. 14, mounted on the actual washing and drying chamber 211 and is so designed that its inlet and outlet directions 208', 208'' form an obtuse angle of deflection α for the circulating drying air which is more than 140° and can amount almost to 180° . The circulating drying air can thereby be better controlled in that allowance is made for the conditions produced by the preceding condensation drying.

For uniform impingement on the articles, the jets of drying air 10 emerging from the orifices 214 of blower 208 into the washing and drying chamber 211 are tilted to and fro over the hanging articles during the drying process so that the articles are struck by the jets of air intermittently. This causes a swaying motion which corresponds to the wind drying of articles hanging in the open air. Furthermore a pleasant finish is obtained through the moving of the articles during drying.

The oscillation of the jets of drying air can be effected in various ways. For example, as shown in FIG. 14, an air-guide baffle 215 arranged to be moved in oscillating fashion can be 20 positioned in the upper part of the washing and drying chamber 211 near the inlet nozzles 214 for the drying air. Depending upon its position, the baffle 215 produces one or two concentrated flat air jets which rotate over the hanging garments. The baffle 215 can be driven by an electric motor 216 25 through a speed-reducing device 217 and a crank arrangement 218 which at the same time can also drive the spray pipes 205, as shown. Instead of a separate electric motor 216, use can be made of the motor 219 which drives the fan member of the blower 208; the gear unit 217 could then be 30 flanged onto the other end of the drive shaft 213 of this electric motor.

On passing through the hanging laundry items, the drying air absorbs moisture by vaporization and in the lower region of 35 the washing and drying chamber 211 it passes through a inlet orifice 220 into the condensation and air-intake shaft 221. The inlet orifice 220 is so designed that air turbulence and thus pressure losses are avoided. Moreover, air swirls at this 40 point would have a very disadvantageous effect in that the downward-flowing cooling water, which passes into the washing and drying chamber together with the condensate, would be carried along by the air current and thus come into contact with the articles, thereby reducing the drying effect. In order to avoid this, the air inlet orifice 220 is made at least twice as 45 large in cross-section as the air shaft 212 and is so designed with regard to the air flow that it co-operates with the base of the washing and drying chamber 211 to guarantee a non-turbulent inflow of air to the air shaft 221. In order to prevent 50 cooling water and condensate from being carried along by the air current in the region of the air outlet orifice 220, there is provided a cooling water guide plate 223 which lies just above the base of the washing and drying chamber 211 and extends partly into the air shaft 221. The purpose of this plate is to 55 keep the condensate and the cooling water which flows down in the cooling water guide fabric 224 completely separate from the air current, particularly in the region of the air outlet orifice 220. For this purpose, the plate 223 covers the lower part of the cooling water guide fabric 224 attached to the outer wall of the air shaft 221, and web being inserted into the 60 space between the plate 223 and the housing wall. The advantageous effect of the cooling water guiding fabric 224 is due in particular to the fact that the adhesive and capillary forces which keep the cooling water and condensate in the fabric are considerably greater than the separating forces for 65 the cooling water and condensate which are caused by the air flow.

A basic feature of appliances in which the laundry is washed and dried in the hanging state is that continuous spaces 226 remain between the articles from top to bottom (FIG. 14) 70 through which the drying air can pass unimpeded and without absorbing the moisture from the wash. This has as a result that a substantial portion of the drying air will pass unused through the washing and drying chamber 211. Both portions of air are then mixed in the condensation and air-inlet shaft 221. In 75 order to eliminate this drawback, which involves a sharply

reduced drying efficiency, the supply of to the cooling water guide fabric 224 is carried out intermittently, the pauses in the supply being so selected that during these pauses a multiple of the overall in volume present in the machine is circulated. The drying air thereby has the opportunity of becoming more saturated with moisture, so that the effectiveness of the condensation drying of the air is correspondingly improved. The ratio of the volume of air supplied by the blower 208 during the cooling pauses to the volume of the container is greater than 1.

Considerable importance also attaches to the drop-and-spray-free path of the cooling water down in the guide fabric 224 in the upper part of the cooling-water sprayer. Spraying of the fabric 224 therefore preferably takes place by a sprinkler 225 located between the fabric and the outer wall of the air shaft 221, the sprinkler 225 being supplied with cooling water from a tank 227. This tank 227 is attached to the water supply by way of a pipe 228 which is provided with a magnetic valve 231. Furthermore, the tank 227 has an overflow outlet which is connected with the washing and drying chamber 211 by a tube or hose 230. The tank 227 has the function of ensuring that the cooling water, issuing for cooling from the fresh-water supply by way of the magnetic valve 231 with variable pressure, has a definite and very low head pressure when it flows out of the apertures of the sprinkler 225 onto the air-shaft surfaces and into the water absorbing fabric 224. The volume of the container 227 is so chosen that even with a very high water pressure it collects the amount of water which emerges from the magnetic valve during the sprinkling period and which then flows out through the outlet pipe 229. The overflow pipe 230 is so dimensioned in cross-section that on the one hand it ensures the necessary pressure equalization with the washing and drying chamber 211 and on the other hand, with the magnetic valve 231 almost permanently open, it lets the fresh water flow into the chamber 211.

Appliances which are almost hermetically sealed in the manner described have the disadvantageous feature that residual water, of which a specific amount remains in the outflow part of the apparatus after pumping, cannot evaporate outwardly of the chamber. With such automatic washing machines this has the result that after switching off at the end of the drying process, vapor originating from the residual water can pass into the washing and drying chamber 211 and the dry washing, which at this temperature has hygroscopic properties, is again moistened although cupboard-dry garments are obtained from the pre-set program. This is particularly disadvantageous if there is a long period, for example of more than 3 hours, between the automatic switching off of the appliance and the removal of the laundry. In order to avoid this disadvantage, the loading door or a ventilator of as large a size as possible may be operated either electromagnetically or thermomechanically. In accordance with the invention, measures are taken in connection with the circuit whereby this system operates so that from time to time, for example every 30 minutes, the air heater 232 is fully or partly switched on and the circulating blower 208 is operated for a short time, e.g., for 2 minutes. Switching on to achieve these measures can be controlled by a hygrometer instead of a timer so that on reaching a predetermined level of atmospheric moisture (for example 80 percent relative humidity) in the processing chamber 211, the blower 208 and the air heater 232 are switched on until the atmospheric moisture has dropped to a second predetermined value (for example 30 percent relative humidity), or until a given temperature of for example 40°C is reached in the processing chamber 211 or until a given interval of time, for example 2 minutes, has passed.

A suitable circuit is illustrated in FIG. 18. A change-over switch 251 operates at the end of the washing and drying cycles to terminate all the functions which are dependent upon the rotation of cam cylinders 258 of the program selector energized via a current-supply line 256. At the same time, the contact 251 in assuming its illustrated position energizes a line 259 in which are included the ventilator 252, a drier and air heater 253 and a control member 254. This control member

254 can be a timer, a bimetallic switch, or a hygrometer. As long as the washing hangs in the machine, after the program has run its course but before the main switch 255 has been opened, the termination contact 251 energizes the electric circuit 259. The control member 254 is set so that, at about every 5 to 30 minutes, it actuates fan motor 252 and heater 253 for a short time, say about 30 seconds, by way of a contact 257. The hanging articles are thereby kept at a somewhat higher temperature level than the rest of the washing and drying chamber so that the laundry does not absorb moisture. Only when the laundry is to be removed, that is, the appliance is turned off by the main switch, the circuit 259 is broken.

A special and complicated problem which arises from combining the washing and drying processes in the same apparatus 15 is that of ventilation and pressure equalization. Whereas for drying in accordance with the principle of condensation from circulated air a pressure-compensating opening from the inner chamber to the outside (located substantially in the neutral-pressure range) should be as small as possible in order to keep the outflow of moisture to a minimum, the rapid temperature alterations which occur during the washing and rinsing process and the undesired pressure effects caused thereby require ventilation over a large cross-sectional area. Also the 20 regulations for ensuring protection of the fresh-water pipes from contamination by reverse suction of dirty water require an overflow with a large cross-sectional area which, in the complete absence of control arrangements, guarantees that the highest possible water level remains a specific minimum 25 distance beneath the pressure-controlled fresh-water outlet. The problems are solved by a specially designed multi-layered loading door 233, examples of which are shown in cross-section in FIGS. 16 and 17. This door 233 locks the washing and drying chamber 211 by way of annulet gasket 234. The door 30 consists essentially of an outer layer 235 and an inner layer 236 bracketing a specially designed pressure-compensating duct 237. The duct 237 has in the case of FIG. 16 a pressure-compensating aperture 238, a condensate separator 239, a condensate reflux 240, a condensation trap 241, an overflow 35 242, a labyrinth 243 and a spray cover 244. The otherwise tightly sealed washing chamber 211 is connected with the outside by way of the pressure-compensating duct 237. Its overall cross-sectional area is so dimensioned that it meets the requirements both of rapid pressure compensation and of an 40 overflow, in accordance with whichever demands the greater cross-sectional area. The pressure compensating aperture 238 lies outside the sealed zone and can be either in the lower region, as illustrated in FIG. 16, or placed higher but still beneath the overflow 242, as illustrated in FIG. 17.

50 The condensate separator 239 is located above the lower limit of the door seal 234. It is formed as an overlap of the inner and outer edges of the duct, so that liquid which passes into the upper part of the duct 237, for example steam condensed during the washing process, drips through an air gap into the lower part of the separator 239 which is formed as a channel 240' and from there passes back through the condensate reflux 240, located above the lower boundary of the door seal, into the washing and processing chamber 211. In order to 55 prevent suds, foam, steam or the like from passing back through the reflux aperture into the pressure-compensating duct 237, for example in the event of pressure impacts from the washing chamber 211, the reflux aperture is sealed by a check valve 245 communicating with the pressure-compensating duct 237 and arranged to be opened by liquid which has gathered in the channel 240'. Beneath the condensate separator 239 and the pressure-compensating aperture 238 there is 60 located the condensate trap 241 which is sealed at its bottom and sides. The very small amount of condensate which collects 65 therein evaporates during the drying process or while the apparatus is out of use. In order to increase the surface area and thus improve the evaporation, the trap 241 contains a foam-like filling 246.

70 The overflow opening 242 is located in the upper region of 75 the pressure-compensating duct 237. Because of its position it

limits the highest possible fluid level in the washing chamber 211 so that even in the event of a so-called dirty-water malfunction, on the failure of all control elements which regulate the supply of water, downward-flowing water passes out of the apparatus via the overflow before it reaches the fresh-water supply. Regulations regarding the protection of drinking water are thereby complied with. The labyrinth 243 which precedes the overflow aperture 242 is used to prevent foam from passing through the overflow opening 242 into the outer part of the pressure-compensating duct 237, for example in the event of very foamy detergents. The profiles in the labyrinth 243 are so designed that they form barriers for the foam which enters the washing and drying chamber 211; during pressure compensation they act as a guide for air coming from the opening 238. In the modified embodiment of the pressure-compensating duct 237 illustrated in FIG. 17, we provide a sponge-like stopper 247 which replaces the labyrinth and presents only a small resistance to the pressure-compensating air flow but on the other hand prevents the foam from passing through. The position of the inlet aperture 248 determines the position of the neutral-pressure zone in the apparatus during drying. The very powerful air currents necessary for a drying process with circulating air require a differential pressure between the suction and delivery sides of about 10 to 12 mm of water column solely to overcome the flow resistance unavoidably experienced throughout the laundry items. In order to keep as small as possible the considerable forces exerted thereby on the container walls and the loading door 233 which define the washing and drying chamber 211, the inlet aperture 248 is located about half-way up the washing chamber. Beneath the inlet aperture 248, a barrier serving as a spray shield 244 is attached to the inner shell 236 of the door. This prevents the washing and rinsing liquid, which issues upwardly from the nozzles of the lower spray pipe 204 at a high velocity, from passing directly into the pressure-compensating duct 237.

A simple time control of the intermittently driven circulating pump cannot make sufficient allowance for the varying activity of the foam which depends on how dirty the garments are, the detergent used, and the temperature of the suds. In order to avoid such a disadvantage, the circulating pump 201 can be switched on by an associated level regulator in dependence on the level of the liquid in the collecting tank 206 or at its intake side, being switched off on the other hand by a suitably arranged pressure-responsive means in dependence on the pressure of the suds prevailing on the delivery side of the pump. It is thus ensured that the circulating pump 201 provides the necessary spray pressure of the suds in the spray pipes 204, 205 for the maximum time. An example of a suitable circuit for this purpose is illustrated in FIG. 19. In this Figure, a cut-in contact 261 is controlled by an associated cam plate of the program selector and enables a lead including the driving motor 263 of the circulating pump to be supplied with voltage by way of a cam-operated switch contact 262. Switch contacts 265 and 266 are in parallel with contact 262. Whereas the switch contact 265 is closed by a level regulator 267, which detects the level of the liquid in the collecting tank 206 of the circulating pump 201, and is opened upon attainment of a specific minimum liquid level, the switch 266 is controlled by a pressure-responsive element 269 installed in the discharge line 268 of the circulating pump 201. During rinsing of the garments, the cam switch 262 is closed so that it bridges the switch contacts 265 and 266 and thus guarantees continuous operation of the electric motor 263 of the circulating pump independently of the condition of the foam. During the washing phase, however, the contact 262 is open. In these circumstances, the driving motor 263 of the pump is turned on by means of the level responsive switch contact 263. Switching on the circulating pump 201 produces a corresponding back pressure of the suds in the pressure line 268 so that the pressure responsive switch 266 is likewise closed. The formation of foam during the washing process rapidly reduces the level of the liquid on the intake side of the pump

75 so that the switch 265 opens although there is sufficient liquid in the pumping system and the pump is still able to produce an effective pressure. Therefore the pump motor 263 is at first still energized by way of the pressure monitoring switch 266.

5 Only when the pressure of the suds in the high pressure line has also dropped below a specific limit does the pressure switch 266 open so that the driving motor 263 stops and thus halts the circulating pump 201. The suds then accumulate in 10 the collecting tank or base trough 206 which is connected in series with the circulating pump 201. As soon as the prescribed liquid level has been reached, the contact 265 is closed by means of a diaphragm switch 267 with the result that 15 the driving motor 263 is again switched on so that the pumping cycle begins anew. FIG. 20 illustrates the development of the cam plates of the program selector which control the contact switches 261 and 262 and it can immediately be seen that the switching contact 261 remains closed for the entire duration of the soaking, washing, and rinsing phases and that the shunt switch 262 is closed only during the rinsing phase.

20 In order to protect certain textile garments, for example a loosely woven wool fabric or a very long-nap sponge-like material which are very sensitive to direct contact with the intense spray jets issuing from the spray pipes 204, 205, from 25 corresponding damage, the garments may be suspended so that they are not directly hit by the spray jets, at least not in the region where they rest firmly on the rods. For this purpose, a suitable form of spray shield may be provided above at least one support rod. A preferred form of such shield, illustrated in 30 FIG. 14, consists of a double array of the comb-like rods 202 over at least a certain region. Rods 202' arranged at the center of the top row thus form the spray shield for sensitive articles which are hung on the rods 202'' located therebeneath. The distance between the upper and lower rods 202' and 202'' is 35 so chosen that the lower rods 202'' always lie in the shadow of the spray of the adjacent upper rods 202'. This arrangement has the additional advantage that normal washable fabrics can always be placed on the upper rods 202' while the sensitive fabrics can be suspended from the lower rods 202''. With 40 bulky articles, such as sheets for example, the upper rods 202' offer the additional advantage that the articles can be more widely spread out and are thus more open to the spray jets.

45 FIG. 21 illustrates, by way of example, a circuit showing a way of increasing the output of the suds heater 207 of FIG. 14 by making constant the electric power demand in relation to the intermittent drive of the circulating pump 201 by motor 263. The driving motor 263 of the pump is switched on by a change-over switch 271 for about 3 seconds and off for about 12 seconds in a constant cycle. In appliances of the type in question, the driving motor 263 of the pump has a power rating of about 1,000 W. In a domestic appliance, which in the majority of cases is connected to a normal wall socket with a 16-amp fuse allowing (at 220 volts) for a total load of 3.5 kWh, this means that only 2,500 W is available for the actual heating. This would therefore result in a comparatively long heating-up time for the suds. In order to avoid this, the suds heater shown in FIG. 21 is divided into two separate heating elements 207' and 207'', one element 207' being permanently 55 switched on during the heating-up period while the other element 207'', whose electrical power consumption preferably corresponds to approximately that of the pump driving motor 263, is switched on only during the standstill periods of the motor 263. This is brought about by the change-over switch 60 271 and its contacts A, B, C and D which are arranged in pairs. This change-over switch thus always turns on the additional heater 207'' immediately upon cutting off the driving motor 263 of the pump, and vice-versa. The entire electric circuit 65 272 can be controlled by a diaphragm switch 273 which operates in dependence on the level of the liquid in the pump ante-chamber or collecting tank 206. FIG. 22 shows, in relation to FIG. 21, a development of the corresponding cam plates of the program selector.

70 What we claim is:

1. An automatic washing machine comprising:

- a front-loading housing forming a treatment chamber for garments to be washed and dried;
- suspension means for said garments in said housing near the top of said chamber;
- spray means in said chamber for irrigating said garments with an aqueous washing solution;
- wall means in said housing forming a narrow air shaft alongside said chamber communicating with the latter at the bottom and at the top thereof, thereby defining a closed air-circulation path;
- blower means in said path for circulating air therethrough with an upward flow through said air shaft;
- sprinkler means at an elevated level in said air shaft for directing jets of cooling water into the rising air flow, thereby promoting the condensation of entrained moisture; and
- a water-absorbing liner on a wall surface of said air shaft positioned to intercept said jets and to guide the water thereof downwardly to the chamber bottom.
2. A machine as defined in claim 1 wherein said liner comprises a textile fabric.
3. A machine as defined in claim 1 wherein said sprinkler means is located at an elevation of substantially two-thirds of the height of said air shaft.
4. A machine as defined in claim 1, further comprising a storage tank at the top of said housing, valve-controlled conduit means connecting said tank with a continuous supply of cooling water, a feed pipe leading from said tank to said sprinkler means, and overflow means extending from said tank to said chamber, thereby maintaining the jets issuing from said sprinkler means at a reduced pressure independent of the supply pressure.
5. A machine as defined in claim 1 wherein said sprinkler means is provided with intermittently operable water-supply means maintained inoperative for periods sufficient to enable recirculation of a multiple of the overall air volume in said closed path.
6. A machine as defined in claim 1 wherein said wall means comprises an upright partition separating said chamber from said air shaft, said liner being disposed on a surface opposite said partition.
7. A machine as defined in claim 6 wherein said sprinkler means is disposed between said liner and an outer wall of said housing supporting said liner.
8. A machine as defined in claim 6 wherein said partition defines with the bottom of said chamber an inlet passage for said air shaft, further comprising drain means at said bottom below said inlet passage.
9. A machine as defined in claim 8, further comprising an apron closely spaced from said wall surface in the region of said inlet passage, said apron overlying a lower portion of said liner extending across said inlet passage.
10. A machine as defined in claim 8 wherein said partition has a bottom edge provided with a water trap for intercepting liquid descending above said inlet passage.
11. A machine as defined in claim 8, further comprising pump means communicating with said drain means for recirculating liquid from the bottom of said chamber to said spray means.
12. A machine as defined in claim 11, further comprising programming means for intermittently operating said pump means for relatively short working periods alternating with relatively long standstill periods.
13. A machine as defined in claim 11 wherein said pump means is provided with intake means and a discharge line, a container between said drain means and said intake means,

- level-responsive first switch means in said container for starting said pump means upon means accumulation of a predetermined amount of liquid ahead of said intake means, and pressure-responsive second switch means in said discharge line for holding said pump means operated independently of said first switch means in response to a predetermined minimum back pressure developed by the recirculating liquid.
14. A machine as defined in claim 11 wherein said spray means includes a rack with upper and lower nozzle in said chamber, further comprising programmed valve means for selectively directing the recirculating liquid at different times to said lower and upper nozzles.
15. A machine as defined in claim 11, further comprising heater means for said liquid at the bottom of said chamber ahead of said pump means.
16. A machine as defined in claim 15 wherein said heater means comprises a first and a second heating element, first circuit means for energizing said first heating element independently of said pump means, and second circuit means for alternately operating said pump means and said second heating element.
17. A machine as defined in claim 1 wherein said blower means is disposed at the top of said housing above said chamber.
18. A machine as defined in claim 17 wherein said air shaft communicates with said chamber at the top via an air passage downstream of said blower means, further comprising oscillatable baffle means in said air passage for directing an air stream in different directions upon said garments.
19. An automatic washing machine comprising:
- a front-loading housing forming a treatment chamber for garments to be washed;
- suspension means for said garments in said housing near the top of said chamber;
- spray means in said chamber for irrigating said garments with an aqueous washing solution;
- a trough at the bottom of said chamber for collecting liquid from said spray means;
- pump means communicating with said trough for recirculating the collected liquid to said spray means; and
- programming means for intermittently operating said pump means during relatively short working periods alternating with relatively long standstill periods.
20. A machine as defined in claim 19 wherein the duration of said standstill periods is at least three times that of said working periods.
21. A machine as defined in claim 19 wherein said pump means is provided with intake means and a discharge line, level-responsive first switch means in said trough for starting said pump means upon accumulation of a predetermined amount of liquid at the chamber bottom, and pressure-responsive second switch means in said discharge line for holding said pump means operated independently of said first switch means in response to a predetermined minimum back pressure developed by the recirculating liquid.
22. A machine as defined in claim 19 wherein said spray means includes a rack with upper and lower nozzles in said chamber, further comprising valve means controlled by said programming means for selectively directing the recirculating liquid at different times to said lower and upper nozzles.
23. A machine as defined in claim 19, further comprising first and second heating means for said liquid in said trough, first circuit means for energizing said first heating means independently of said pump means, and second circuit means for energizing said second heating means only during said standstill period.
